DESIGN FOR A LOCOMOTIVE BODY

Otto Kuhler, Orangeburg, N. Y., assignor to American Locomotive Company, New York,
N. Y., a corporation of New York

Application January 26, 1940, Serial No. 89,740

Term of patent 14 years

To all whom it may concern:

Be it known that I, Otto Kuhler, a citizen of the United States and resident of Orangeburg, in the county of Rockland and State of New York, have invented a new, original, and ornamental Design for a Locomotive Body, of which the following is a specification, reference being had to the accompanying drawings which form a part thereof.

represents a front end elevational view of the locomotive body; Fig. 3 represents a perspective view of the front portion of the locomotive body; and Fig. 4 is a side elevation on a reduced scale of a locomotive body showing my new design.

The portions of the figures shown in full black lines show the dominant features of the design.

I claim:

The ornamental design for a locomotive body, substantially as shown and described.

OTTO KUHLER.
